(57) **CLAIM**

The ornamental design for a paint can funnel, as shown and described.

DESCRIPTION

FIG. 1 is a top perspective view of the article being made of a transparent material according to first embodiment of a paint can funnel showing our new design;

FIG. 2 is a bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a top perspective view of the article being made of an opaque material according to a second embodiment of a paint can funnel showing our new design;

FIG. 10 is a bottom perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof; and,

FIG. 16 is a bottom view thereof.

The portions shown in dashed lines form no part of the claimed design.

1 Claim, 10 Drawing Sheets
